No. 842,045

PATENTED JAN. 22, 1907.

D. B. WHISTLER.

OPERATING MECHANISM FOR FARE REGISTERS AND RECORDERS.

APPLICATION FILED SEPT. 19, 1906.

UNITED STATES PATENT OFFICE.

DAVID B. WHISTLER, OF DAYTON, OHIO, ASSIGNOR TO THE RECORDING AND COMPUTING MACHINES COMPANY, OF DAYTON, OHIO, A CORPORATION OF OHIO.

OPERATING MECHANISM FOR FARE REGISTERS AND RECORDERS.

No. 842,045.

Specification of Letters Patent.

Patented Jan. 22, 1907.

Application filed September 19, 1906, Serial No. 335,243.

To all whom it may concern:

Be it known that I, DAVID B. WHISTLER, a citizen of the United States, residing at Dayton, in the county of Montgomery and State of Ohio, have invented certain new and useful Improvements in Operating Mechanism for Fare Registers and Recorders, of which the following is a specification, reference being had therein to the accompanying drawings.

This invention relates to operating mechanism for fare registers and recorders, and more particularly to operating mechanism for devices of that class wherein the register is set to the particular fare to be registered by means of a rotating shaft, the actual registering or actuation of the registering mechanism being accomplished by a reciprocating or oscillating part after the register is set. Machines of this type are illustrated, for instance, in an application filed by Wilfred I. Ohmer, December 27, 1904, Serial No. 238,346, and in an application filed by said Wilfred I. Ohmer jointly with Albert J. Kirchner and John W. Hill, December 16, 1905, Serial No. 292,068, both of which applications are assigned to The Recording and Computing Machines Company, the assignee of the present application. In these machines, which are adapted for use on interurban lines, provision is made for dealing with a large number of different specific fares, the last-mentioned application dealing, for instance, with twenty-four different specific fares.

It is the object of the present invention to provide a simple and compact mechanism which will take up a relatively small space in the car-body in which it is mounted and which shall not only serve to set and actuate the register, but also to indicate at different points in the car the particular fare which the machine is set to register, so that both the conductor and passengers may readily know the fact.

To this end my invention consists in certain novel features which I will now proceed to describe, and will then particularly point out in the claims.

In the accompanying drawings, Figure 1 is a plan view of a mechanism embodying my invention in one form. Fig. 2 is an enlarged

elevation of one section of the same. Fig. 3 is a detail sectional view taken on the line *x x* of Fig. 1 and looking in the direction of the arrows. Fig. 4 is a similar view taken on the line *y y* of Fig. 1 and looking in the direction of the arrows, and Fig. 5 is a front elevation of the device as shown in Fig. 1.

In the said drawings, 1 indicates the side wall of the car-body, to the inner face of which are secured, at each end thereof, brackets 2, in which is mounted a shaft 3, which is connected with the setting-shaft of the register by means of any suitable gearing, so that rotation of said shaft 3 will set the register to any desired fare. The shaft 3 is provided at suitable intervals with hand-grasps 4, of any suitable construction, by means of which said shaft may be readily rotated. Near each of its ends the shaft 3 is provided with a bevel-gear 5, located adjacent to the bracket 2, and each bevel-gear 5 meshes with a bevel-gear 6, secured on a shaft 7, which is mounted in an arm 8 of the adjacent bracket 2. Each shaft 7 has secured to it a winding wheel or drum 9, to which is secured one end of a flexible connection 10, forming part of the indicator. Said flexible connection may be of any suitable description, such as a cord, rope, wire, chain, or the like. The winding wheels or drums are preferably spirally grooved, as indicated at 11, to cause these flexible connections to wind and unwind properly when the apparatus is in use.

The shaft 3 is supported at various intermediate points between the brackets 2 by means of intermediate brackets 12, secured to the wall 1, and these intermediate brackets are apertured for the passage of an index bar or rod 13, to the ends of which the other ends of the flexible connections 10 are secured in any suitable manner. The index-bar carries at suitable intervals indices or pointers 14, which are secured thereon, preferably between each pair of intermediate brackets 12, and said pair of intermediate brackets support between them an indicating-scale 15, subdivided into equal spaces, on which the various fare denominations are shown in any suitable manner. The index-bar is located behind the indicating-scales 15, and the index or pointer for each scale extends forward under the lower edge of the

scale and then upward on the face of the same a distance sufficient to be plainly visible in connection therewith. As the apparatus is generally arranged at a considerable height in the car, the indicating-scales are inclined, as shown, so that their indicating-faces will be readily visible from below.

It will be seen that when the shaft 3 is rotated to set the register the winding wheels 10 or drums 9 will be rotated in a corresponding direction, both wheels rotating in the same direction, and it will also be observed that the flexible connections 10 are wound around said wheels in opposite directions, so that 15 when said wheels are thus rotated the flexible connection at one end will be wound upon its wheel, while the flexible connection at the other end will be unwound from or paid out by its wheel to a corresponding extent, so 20 that the index-bar is moved in one direction or the other, according to the direction in which the shaft 3 is turned and to an extent proportionate to the extent of angular movement of said shaft. The parts of the operating mechanism are so proportioned and adjusted relatively to those of the register that 25 the pointers 14 will always be located opposite those particular divisions of the indicating-scales which show the fare denomination 30 corresponding to the fare for which the register is set, so that such fare will be prominently indicated at different points in the car, and the conductor can readily see that the register is set for the desired fare, while the passenger can also note that the proper fare is indicated. Incidentally it may be noted that 35 the register is provided with a suitable detent mechanism for holding the setting mechanism in proper position for each fare, and 40 this detent mechanism enables the conductor to determine when the setting mechanism is in proper position by the varying resistance offered to the rotation of the shaft 3.

The operation of the register may be effected by means of an operating rope or cord 45 16, connected to the actuator of the register and passing through apertured supporting and guiding lugs 17, carried by the brackets 2 and 12.

50 It will be noted that the mechanism is simple and efficient and at the same time very compact, taking up but little wall-space on the car, while it is adapted to indicate a large number of different specific fares in such a way that they will be plainly visible.

I wish it to be understood that I do not desire to be limited to the exact details of construction shown and described, for obvious modifications will occur to a person skilled in 60 the art.

Having thus fully described my invention, what I claim as new, and desire to secure by Letters Patent, is—

1. An operating mechanism for fare-registers comprising a rotatable shaft adapted for

connection with the setting mechanism of a register, winding wheels or drums driven from said shaft, and an indicator extending substantially parallel to said shaft and comprising flexible end portions wound on said 70 wheels or drums, and an intermediate portion provided with an index or pointer, and an indicating-scale coöperating with said index or pointer, substantially as described.

2. An operating mechanism for fare-registers comprising a rotatable shaft adapted for connection with the setting mechanism of a register, winding wheels or drums driven from said shaft, and an indicator extending substantially parallel to said shaft and comprising flexible end portions wound on said 75 wheels or drums, and an intermediate portion provided with a plurality of indices or pointers, and a corresponding plurality of indicating-scales coöperating with said indices 80 or pointers, substantially as described.

3. An operating mechanism for fare-registers comprising a rotatable shaft adapted for connection with the setting mechanism of a register, winding wheels or drums driven 90 from said shaft, and an indicator extending substantially parallel to said shaft and comprising flexible end portions wound on said wheels or drums, and an intermediate index-bar provided with an index or pointer, means 95 for supporting and guiding said index-bar, and an indicating-scale coöperating with said index or pointer, substantially as described.

4. An operating mechanism for fare-registers comprising a rotatable shaft adapted for 100 connection with the setting mechanism of a register, winding wheels or drums driven from said shaft, and an indicator extending substantially parallel to said shaft and comprising flexible end portions wound on said 105 wheels or drums, and an intermediate index-bar provided with a plurality of indices or pointers, a corresponding plurality of indicating-scales coöperating with said indices or pointers, and brackets supporting and guiding 110 said index-bar, and carrying the indicating-scales, substantially as described.

5. In an operating mechanism for fare-registers, a rotatable setting-shaft, in combination with end brackets supporting said 115 shaft, winding wheels or drums also supported on said end brackets, gearing connecting said shaft and wheel's to cause them to rotate in unison, and an indicator extending substantially parallel to said shaft and comprising flexible end portions wound on said wheel's or drums; and an intermediate rigid portion provided with an index or pointer, and an indicating-scale coöperating with said index or pointer, substantially as described. 120

6. In an operating mechanism for fare-registers, a rotatable setting-shaft, in combination with end brackets supporting said shaft, winding-wheels also supported on said end brackets, gearing connecting said shaft 125

and wheels to cause them to rotate in unison, and an indicator extending substantially parallel with said shaft and comprising flexible end portions wound on said wheels or drums, 5 and an intermediate index-bar provided with a plurality of indices or pointers, a corresponding plurality of indicating-scales coöperating with said indices or pointers, and intermediate brackets supporting said shaft and in-

dicating-scales and also supporting and guiding the index-bar, substantially as described.

In testimony whereof I affix my signature in presence of two witnesses.
